UNITED STATES PATENT OFFICE.

EDWARD A. CASWELL, OF NEW YORK, N. Y.

BED-FENCE.

SPECIFICATION forming part of Letters Patent No. 367,186, dated July 26, 1887.

Application filed February 9, 1887. Serial No. 227,081. (No model.)

To all whom it may concern:

Be it known that I, EDWARD A. CASWELL, residing in New York, N. Y., have invented a species of bed-fence, intended to secure greater personal comfort and more restful repose for such persons as are by circumstances forced to occupy one bed together.

This invention has relation to what may be termed a "bed-fence."

10 The object of the invention is to provide a device which may be arranged in a bed longitudinally and at about the center, for the purpose of dividing the bed into two portions, each being sufficient for a single occupant.

15 It is well known that some persons have habits, such as carelessly throwing the limbs from side to side of the bed while sleeping therein, to the discomfort of another occupant of the same bed; and it is well known 20 that it is considered injudicious for persons to lie in a bed facing each other in such relative positions that the one will inhale the breath of the other. Furthermore, the habit of snoring is, in a great measure, dependent upon the 25 habit of lying upon the back. Any device which will contribute to the prevention of the inhalation of the breath of a bed companion, and which will prevent a person from assuming a position tending to produce snoring while 30 sleeping, and which shall, without discomfort to either of the occupants of a bed, divide said bed into separated compartments, will possess material advantages and in a great measure tend to the promotion of restful sleeping and 35 more perfect health.

Having the above general objects in view, I believe I am the first to produce any device which is adapted to the purpose in view, and I therefore do not limit my invention to the 40 exact construction hereinafter described.

One of the main requisites of any device intended for the purpose of my invention is that it shall be capable of use without interfering with the make-up and construction of an ordinary double bed and without interfering with the comfort of either of two occupants of such bed.

Referring to the drawings, Figure 1 represents one form of a device capable of performing the required functions and possessing the necessary requisites of my invention. Fig. 2

is a transverse section of the same folded for transportation or reduction of the space occupied by the same. Fig. 3 is a transverse vertical section of the same in position for use. 55

Like letters indicate like parts in all the figures.

A represents a slab or strip of any suitable material—such as, for example, wood or paper—which strip or slab is of a length approaching that of the bed in which it is used—that is to say, the length of the entire device may be equal to or less than that of the bed. At the ends of the strip A are secured in any suitable manner flexible straps B, of cloth or 65 other material, and in the straps B, in this instance, I form a button-hole, B', so that the straps may be connected to the mattress, or to any other convenient portion of the bed-clothing, which is provided with a hook or button 70 in order to retain the device in position for use. At each edge of the strip A are secured similar strips, C D, respectively, of substantially the same length as the strip A and of a desired width. The strips C and D are secured by 75 means of metallic or other hinges, C'D', so that the side strips, C and D, may be folded flat, as shown by dotted lines in Fig. 1, or upon each other upon the strip A, as shown in Fig. 2, or so that the free edges of said strips may rest 80 against each other, and in this manner serve to retain the strips in an elevated position. Hook-pins or other side-strip-securing devices, C', may be employed. When thus elevated, it will be noticed that when placed upon a mat- 85 tress beneath the lower sheet, or, it may be, upon the lower sheet of the bed-clothing, the device forms a partition, division, wall, or fence, which prevents the trespass by one occupant of a bed upon the portion occupied by 90 another.

The device, also, in a great measure prevents the inhalation by one occupant of the breath of another when sleeping face to face, and it also will serve the purpose of preventing a person who has taken a sleeping posture upon his or her side from rolling over onto his or her back, and thus in a measure is snoring avoided.

When it is not desirable to use the device, 100 it may be laid flat, as shown by dotted lines in Fig. 1, when, by reason of the usual under-

sheet and under-comforter employed in ordinary bed-clothing, the device will in no material degree affect the comfort of the bed to the occupants thereof.

My device is useful not only in private

houses, but in hotels, where strangers are often

compelled to jointly occupy one bed.

It is apparent that my device will perform its primary function as a divisional partition in a bed without necessarily being capable of folding flat; and I therefore do not limit my invention to the provision of hinges, and I may, when such are employed, construct them of cloth, leather, or other flexible material, as shown at D', Fig. 2, whereby when folded upon each other the sides will rest parallel with each other and with the slab A.

Instead of buttoning the straps B to the mattress or to the comforter or sheet or other portion of the bed-clothing, said straps may be secured to the head and foot boards of the bed.

The flexibility of the straps and their extension beyond the fence permits this latter attachment without separating the bed-clothing to an extent sufficient to admit the external air in a degree which will render the occupants uncomfortable.

Having described my invention, its construction and operation, what I claim is:

1. A fence for a bed, comprising a flat base 30 for supporting the fence upon the mattress, a portion projecting upward from the base, and attaching devices secured to the end of the base, substantially as specified.

2. A bed-fence comprising sections, one of 35 which serves as a flat base for supporting the fence upon the mattress, and is provided with attaching devices, and the others of which serve as an upwardly-projecting partition, substantially as specified.

3. A bed-fence consisting of a base provided with attaching devices and foldable side pieces connected with the base, substantially as specified.

4. The bed-fence herein shown and described, 45 which consists of the base, strip, or slab A, provided with attaching straps B, and with the hinged side strips, C D, substantially as specified.

E. A. CASWELL.
